CLAIM

The ornamental design for a compartmented trash receptacle, as shown and described.

DESCRIPTION

FIG. 1 is a front elevational view of a compartmented trash receptacle showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a top perspective view thereof, the lid of the receptacle being elevated for clarity of illustration.

FIG. 1

FIG. 2

FIG. 3

FIG. 4

FIG. 5

FIG. 6
